UNITED STATES PATENT OFFICE.

HARRY B. SNELL, OF TOLEDO, OHIO, ASSIGNOR TO THE SNELL-JUDD COMPANY,
A CORPORATION OF OHIO.

ACTUATING MECHANISM FOR ELECTRIC SWITCHES.

No. 883,150.

Specification of Letters Patent. Patented March 24, 1908.

Application filed January 26, 1907. Serial No. 354,175.

To all whom it may concern:

Be it known that I, HARRY B. SNELL, of Toledo, county of Lucas, and State of Ohio, have invented certain new and useful Improvements in Actuating Mechanisms for Electric Switches; and I do hereby declare that the following is a full, clear, and exact description thereof, which will enable others skilled in the art to which it appertains to make and use the same, reference being had to the accompanying drawings, and to the figures of reference marked thereon, which form part of this specification.

This invention has reference to mechanisms for actuating electric switches, the mechanism being especially adapted for operating snap-switches employed to light and extinguish the incandescent lamps in store windows at predetermined hours.

In carrying out my invention, I employ the novel combination arrangement and details of construction hereinafter shown, described and claimed.

In the accompanying drawings, Figure 1 is a plan view of my complete mechanism; Fig. 2 is a front elevation of the same.

Referring to the details, the frame for the mechanism comprises a base 1 and a vertical supporting wall 2, both preferably cast in one piece to insure rigidity. Upon the plate 2 is supported a clock movement confined within a case 3, the movement actuating a spindle 4 to rotate the same once in twenty-four hours. Secured upon the spindle 4 to rotate therewith is a dial-plate 5 which is graduated and numbered to indicate the twenty-four hours of the day. Carried upon the spindle 4 to rotate therewith and complete a single rotation in twenty-four hours are disks 6 and 7 having smooth peripheries, the periphery of each disk being indented by a notch or recess indicated at 8 and 9 respectively. The disks are independently rotatable or adjustable upon the spindle 4, and when adjusted 45 with respect to the notches are secured by a nut 10 upon the outer end of the spindle.

11 and 12 are levers pivoted at 13 and 14 respectively, the ends 15 and 16 of the levers having teeth 17 and 18, the tooth 17 being adapted to ride upon the periphery of the disk 6 and enter the notch 8 and the tooth 18 being adapted to ride upon the periphery of the disk 7 and enter the notch 9.

19 is a coiled spring having its ends connected to the levers 11 and 12 to cause the

ends 15 and 16 of the levers to lie in resilient contact with the peripheries of the disks 6 and 7 respectively. The end 20 of the lever 11 will be elevated to the position *a* in dotted lines when the tooth upon its opposite end 60 enters the notch 8, and the end 20 is provided with a shouldered catch or hook 21 adapted when in its normal lowered position, in full lines, to engage one or the other of shoulders 22 and 23 provided at diametrically opposite points of a cam-disk 24, keyed or otherwise secured upon a spindle 25 which on being rotated by quarter turns operates a snap switch 26 of ordinary construction, the switch being of that character which is 70 turned off and on successively by successive quarter rotations of its actuating element.

The cam-disk 24 is rotated in the direction of the arrow by a band spring 27 having its inner end secured to the spindle 25 and its 75 outer end to a spring-case 28 provided with a gear 29 adapted to be engaged by a small gear 30 carried upon a winding spindle 31, the latter being rotated by an ordinary crank, engaging the squared outer end thereof. 80 The end 32 of the lever 12 is pivotally connected with an L-lever 33 pivoted at 34, the end 35 of the free arm of the lever 33 being disposed relative to the end 20 of the lever 11 at a quarter distance about the periphery 85 of the cam-disk. As a result of this arrangement the shoulder 22 of the cam-disk, when released from the hook 21 at the end of the lever 11, will rotate through a quarter turn and be arrested by striking the end 35 of the lever 90 33. When the tooth 18 of the lever 12 enters the notch 9 in the periphery of the disk 7, the opposite end will assume a position *b* in dotted lines, the lever 33 also altering its position, shown in dotted lines, and releasing 95 the shoulder 22, thereby permitting the cam-disk to rotate through a quarter turn a second time, the rotation of the cam-disk being now checked by the hook on the end of the lever 11 engaging the shoulder 23, the latter 100 having in the mean time advanced to the position previously occupied by the shoulder 22. In this manner one of the shoulders upon the cam disk will be out of engagement when the other is engaged. It is thus seen, 105 when the notches in the disks 6 and 7 are properly positioned opposite the numerals on the dial-plate corresponding to the time at which the lamps are to be lighted and extinguished, that such lighting and extin-

110

guishing will take place at the hours indicated.

In the illustration of the mechanism, the notched disks are positioned to light the lamps at 5 o'clock, the tooth at the end of the lever in contact with the disk 6 entering the notch in said disk at that hour, and releasing the cam-disk. At 11 o'clock the notch in the disk 7 will arrive at a position at which the tooth upon the end of the lever 12 will enter it and release the cam-disk a second time. The arrangement of the mechanism is extremely simple and effective, the employment of independently operated levers to successively arrest and release the cam-disk being especially effective.

Having described my invention, what I claim and desire to secure by Letters Patent, is:—

20 In a switch-actuating mechanism, a clock, a pair of disks rotated thereby to complete one rotation in twenty-four hours, each provided with a notch in its periphery, a pair of substantially parallel levers having their 25 ends in spring-pressed contact with the peripheries of the notched disks and having

projections adapted to enter the notches, a spring-rotated switch carrying a cam-disk provided with oppositely disposed shoulders, the end of one of said parallel levers being 30 provided with a hook-shaped end in the path of the shoulders of the cam-disk, an L-lever pivoted to the end of the other parallel lever and disposed in the path of the shoulders of the cam-disk, the end of the 35 L-lever adapted to engage and release the shoulders of the cam-disk being arranged relative to the hook-shaped end of the first parallel lever at a quarter distance about the periphery of the cam-disk, whereby the 40 shoulders of the cam-disk will be successively engaged and released and intermittent quarter movements imparted to the cam-disk, substantially as described.

In testimony, that I claim the foregoing as 45 my own I affix my signature, in presence of two witnesses.

HARRY B. SNELL.
